UNITED STATES PATENT OFFICE.

WILLIAM I. BALLENTINE, OF PHILADELPHIA, PENNSYLVANIA.

PROCESS OF TESTING THE HARDNESS AND DENSITY OF METALS AND OTHER MATERIALS.

No. 855,923.

Specification of Letters Patent.

Patented June 4, 1907.

Application filed October 18, 1906. Serial No. 339,441.

To all whom it may concern:

Be it known that I, WILLIAM I. BALLENTINE, a citizen of the United States, residing in Philadelphia, Pennsylvania, have invented 5 certain Improvements in Processes of Testing the Hardness and Density of Metals and other Materials, of which the following is a specification.

The object of my invention is to improve 10 the process of testing the hardness or density of metals and other materials.

The usual practice is to impress a ball into 15 the metal to be tested and the depth of the impression is measured, but this method is 20 unsatisfactory and to a certain extent uncertain as in most cases the test is made on a separate test piece of the metal and furthermore the testing machine is not portable so that it is difficult to make a test of a large 25 casting or forging.

By my improved process an impression is 30 made by a definite force on a blank preferably of a softer metal than the metal being tested and this blank is calibered, the test can 35 be made upon the metal at any point desired as the process can be readily carried out in a portable device and the test will not injure or 40 disfigure the metal being tested.

In the accompanying drawings: Figure 1 is 30 a vertical sectional view of an apparatus which may be used in carrying out my improved process; Fig. 2 is an inverted sectional view on the line 2—2, Fig. 1; Fig. 3 is a dia- 35 grammatic view showing the relation of the punch and plunger before the impression is made; Fig. 4 is a view similar to Fig. 3, after the impression is made; Fig. 5 is a perspective view of the test disk before being acted 40 upon by the punch; and Fig. 6 is a perspective view of the test disk after being acted upon by the punch.

Referring to the drawings, A is a tubular 45 guide which may be of any length desired. Secured to the bottom of this guide is a block a which is shaped to receive the punch B. This punch has a blunt point b at one end and a flat head b' at the opposite end and reduced at the center b². The head b' is greater in diameter than the point b.

a' is a screw stop which passes through the 50 block a and into the cavity for the punch, limiting the movement of the punch.

D is a plunger adapted to slide freely in the 55 tubular guide A and in order that it may slide more freely, it is provided with guide ribs d as indicated in Fig. 2, leaving an air space

between the plunger and guide. In the bottom of the tube are openings a² for the escape of air when the plunger descends.

C is a trigger pivoted at c to the tube A. 60 The end of this trigger when the plunger is raised, as in Fig. 1, enters an annular groove d' in the plunger D, and I preferably secure to one side of the tube A a spirit level g which will indicate when the tube is plumb. The 65 lower end of the plunger D is preferably tapered as shown at d² and has a screw-threaded end.

E is a cap fitting the screw-threaded end and having an opening e larger in diameter 70 than the end b' of the punch B. Secured by the cap E is the test disk I of lead or other material softer than the metal of the object to be tested. The cap is beveled at e' so that when the cap is screwed down upon the disk 75 it will center the disk on the plunger. The disk is of less diameter than the inner diameter of the cap to allow it freedom to expand when it strikes the punch B.

In carrying out my improved process a 80 chart is made indicating the different densities of metal according to the difference in the compression of the disk I. The disks I find most satisfactory are of pure lead, as this metal runs more evenly than an alloy 85 and consequently the reading is more accurate. If, for instance, a casting is to be tested as to its hardness and density, the punch B is placed in the tube as indicated in Fig. 1, and the disk I is secured to the end of 90 the plunger D and the plunger is mounted in the tube, being held in its raised position by the trigger C. The device is then placed over the portion of the casting to be tested and is plumbed so as to be in a vertical position. Then the trigger is compressed so as to release the plunger which drops directly on to the enlarged end b' of the punch B so as to exert a definite force thereon, driving the small end b of the punch into the casting 95 a certain distance, the enlarged head b', however, embedding itself in the disk I as indicated clearly in Fig. 4. The amount of penetration of the disk will depend upon the amount of penetration of the metal being 100 tested. If the metal is very hard the punch will make very little impression on the casting and the disk will be compressed to a greater extent than if the punch penetrated the casting to a greater depth. The plunger 105 is then withdrawn and the disk I is removed. It is then calibered to find the thickness of

metal which was under compression and it is the thickness between the head of the punch and the end of the plunger which will indicate in comparing with the chart the 5 hardness of the casting being tested.

It will be seen that such a process is very accurate and that the device for carrying out the process is portable and can be used in making a number of tests on the same piece 10 without the necessity of re-adjusting the piece.

It will be understood that while I have described a particular form of apparatus for carrying out my improved process the apparatus 15 may be modified without departing from the essential features of the invention.

I claim:

1. The process of testing the hardness or density of materials which consists in transmitting 20 a predetermined testing force to the material under test through two bodies, of which one is softer and the other is harder than the material to be tested, and then measuring the resulting deformation of the 25 softer of said two bodies, substantially as described.

2. The process herein described of testing metals and other materials, said process consisting in transmitting a definite pressure to

the material tested through a body of material softer than that under test and thereby recording the effect of such pressure by compressing said softer material, and measuring the amount of compression of the soft material, substantially as described. 30

3. The method of testing the hardness of materials, which consists in delivering a blow of predetermined force to the materials under test, said blow being transmitted through two bodies, of which one is softer than that 40 tested, and then measuring the amount of deformation of said softer body, substantially as described.

4. The method of testing the hardness of materials, which consists in transmitting the 45 force of a body falling freely through a predetermined distance under the influence of gravity, through a piece of relatively soft material, and then measuring the resulting deformation of said soft piece, substantially as 50 described.

In testimony whereof, I have signed my name to this specification, in the presence of two subscribing witnesses.

WILLIAM I. BALLENTINE.
